UNITED STATES PATENT OFFICE.

WILLIAM H. SALADEE, OF BEDFORD, INDIANA, ASSIGNOR OF ONE-HALF TO OLIVER McLAHLAN, OF OOLITIC, INDIANA.

TOY.

1,122,221.

Specification of Letters Patent. Patented Dec. 22, 1914.

Application filed September 21, 1914. Serial No. 832,638.

To all whom it may concern:

Be it known that I, WILLIAM H. SALADEE, a citizen of the United States of America, residing at 1335 Ninth street, Bedford, in the county of Lawrence and State of Indiana, have invented certain new and useful Improvements in Toys, of which the following is a specification.

This invention relates to toys, and one of the principal objects of this invention is to provide a toy which will simulate a number of cowboys dancing upon a platform and raising revolvers, and means for operating the toy by hand.

Another object of the invention is to provide an amusement toy which shall be of simple construction and which can be readily operated by hand and which can be produced at a comparatively low cost.

These and other objects may be attained by means of the construction illustrated in the accompanying drawing, in which:

Figure 1 is a perspective view of the toy and Fig. 2 is a central vertical section of the platform and a portion of the central tube, the men being removed.

Referring to the drawing the numeral 1 designates a platform which may be circular or other shape, and connected to the platform is a casing 2 said casing being connected underneath the platform and provided with a closed head 3. A tube 4 extends through the casing and through the platform, said tube having a handle 5 at its lower end. The tube 4 extends loosely through the the platform and casing, and a collar 7 inside the casing serves as a stop to limit the upward movement of the casing. At the upper end of the tube 4 is a threaded portion or pin 8 and mounted on said pin is a support or hanger 8 having four equidistant arms, having at their outer ends inwardly extending hooks 9 and spaced some distance therefrom having outwardly extended hooks 10. A spring 6 surrounds the tube 4 within the casing 2 and bears at one end against the collar 7 while the opposite end bears against the underside of the

platform. The cowboys and the tenderfoot 12 are suspended from the bars 9 by means 50 of eyes 13 and the bars 9 are adjustable relatively to the platform by the threaded pin. The arms and legs of the cowboys and tenderfoot are flexible and hence will assume various movement of the platform. 55 The platform is moved relatively to the men by means of a cord or wire 14 which extends through the handle and through the tube 4 and the upper end of the cord or wire is connected to a wire clip or fastener 15 extending through the tube 4 and secured to the platform 1. The tube 4 is slotted at 16 to permit the clip to move up and down in the tube.

From the foregoing it will be obvious 65 that the toy will be operated by pulling the string or wire 14 to pull the platform down slightly and by letting the string go the men are made to dance and assume all sorts of grotesque positions. 70

Various changes may be made in the detail of the construction without departing from the spirit and scope of the invention as defined in the claims.

What is claimed is;—

1. A dancing cowboy toy comprising a platform, a casing connected to the platform, a tube extending through the casing and platform and provided with a handle, a supporting bar adjustably connected to the upper end of the tube and provided with outwardly and inwardly extending hooks, and figures of men being suspended from the supporting bars and means for moving the platform up and down relatively to the men. 75

2. A dancing cowboy toy comprising a tube, a platform mounted loosely on the tube, a supporting member at the upper end of the tube, dancing figures loosely suspended from the member, and means for raising and lowering the platform relatively to the bar. 80

3. A dancing toy comprising a hollow tube, a platform slidably mounted on said tube, a slot in the tube, a bracket secured 90

95

to the platform and extending through said slot, a shoulder on said tube, a spring surrounding the tube between the shoulder and the platform, a supporting member adjustably mounted on the upper end of said tube, dancing figures mounted on the supporting member, and a cord secured to said bracket and extending through the tube, the cord

being adapted for moving the platform against the expansion of the spring. 10

In testimony whereof I affix my signature in presence of two witnesses.

WILLIAM H. SALADEE.

Witnesses:

CRAWFORD JOHNSON,
EZRA SIBERT.
